MUSICAL CHIME SIGNAL CONSTRUCTION

Christian Miller, Norwalk, Conn., assignor to
 Edwards and Company, Inc., Norwalk, Conn., a
 corporation of New York

Application December 21, 1945, Serial No. 636,482

5 Claims. (Cl. 84—404)

1

This invention relates to musical chime signalling construction.

One of the objects of this invention is to provide a simple, practical, and reliable mechanically-actuated musical chime mechanism that will be capable of dependable actuation through a wide range of thicknesses of door panels or the like on which it is mounted, and actuatable by a simple type of manual movement from the exterior of the panel. Another object is to provide a device of the above-mentioned character in which the external actuator may be constructed to simulate a door knocker and in which the sounding mechanism on the other side of the door panel is actuatable thereby by simple and efficient mechanism operable throughout varying thicknesses of door panel. Another object is to provide a musical signalling apparatus of the above-mentioned character that will be of inexpensive and lasting construction, dependable action, and well adapted to meet widely varying conditions of practical installation. Another object is in general to improve the construction and action of musical signalling mechanisms, and other objects will be in part obvious or in part pointed out hereinafter.

The invention accordingly consists in the features of construction, combinations of elements, arrangements of parts as will be exemplified in the structure to be hereinafter described and the scope of the application of which will be indicated in the following claims.

In the accompanying drawing, in which is illustratively shown in preferred embodiment of my invention,

Fig. 1 is a front elevation of the chime signalling device as seen with the cover removed;

Fig. 2 is a fragmentary vertical sectional view as seen along the line 2—2 of Fig. 1, showing the cover in position and the entire mechanism as installed and ready for operation;

Fig. 3 is a fragmentary sectional view or elevation as seen along the line 3—3 of Fig. 2; and

Fig. 4 is a front elevation, as seen from the right in Fig. 2, of that portion of the mechanism that is external of the door or other panel.

Similar reference characters refer to similar parts throughout the several views of the drawing.

I preferably provide a base plate 10 of sheet metal, preferably peripherally flanged, as at 11, to rest against a vertical surface such as the inside face of a door panel 12 (Fig. 2) to which the device may be secured, as by screws, the base 10 having suitable holes 13 for that purpose.

2

Along the respective longitudinal side edges of the base 10 are supported two vibratable sounding elements 14 and 15, illustratively taking the form of elongated metal plates or bars, preferably differently dimensioned so as to emit distinguishing musical tones. The elements 14 and 15 are thus spaced from each other and are preferably parallel, and may be supported in such relation to the base 10 in any suitable way as, for example, by L-shaped brackets 16 (Fig. 1) of sheet metal secured in any suitable way to the base 10, as by providing them with feet 16a which are spot-welded to the sheet-metal base 10; at their outer ends the brackets 16 are provided with suitable means, including bushings 17, of rubber or other resilient or cushioning material, that extend through suitable holes in the sounding elements 14, 15, thereby also voiding damping of their tone-emitting vibration.

20 I provide a striker 18 for impacting the sounding elements in response to the actuation of an external manual actuator 19 mounted on the other face of the door panel 12 (see Fig. 2) and constructed or arranged to simulate a door knocker in that it is mounted to pivot at its upper end about a horizontal axis. More particularly, the external actuator 19 may comprise an elongated lever 20 (Figs. 2 and 4) pivotally carried by a pin 21 between spaced lugs 22—23 (Fig. 4) which are formed integrally with a suitably shaped and preferably ornamental plate 24 which may be secured against the outside face of the panel 12, as by screws 25. The plate 24, in between the lugs 22—23, has therein a vertical slot 26 of substantial vertical extent, and through the slot 26 extends a stiff or rigid bar or rod 27 which is rigidly secured to the lever arm 20 at substantially right angles thereto and preferably at a point materially displaced (upwardly in Fig. 2) from the pivoting axis 21 of the actuator arm 20, and with that preferred relationship, swinging of the arm 20, throughout a relatively small angle, transmits to the rod 27 a combined motion of translation and of pivoting, giving the inner or left-hand end of the rod 27 a substantial range of movement in an up and down direction. The lower end of the actuator arm 20 may be provided with any suitable hand or finger grip, such as a cross-bar 28, which may be readily grasped and swung outwardly (counter-clockwise in Fig. 2), throughout a suitable and preferably small angle, from its normal innermost position.

40 The external actuating mechanism will thus be seen to be of simple and inexpensive construc-

50

tion and may be made up as a single entity, with the lever rod 27 of substantial length, and it will be seen that the device, after drilling a suitable large hole 12^a through the panel 12 for the passage therethrough of the rod 27, may be readily and quickly mounted in position on the outside face of the door panel 12. A substantial portion of the rod 27, depending upon the thickness of the door panel 12 met with, thus projects inwardly from the inner face of the door panel 12 and is received through a long vertical slot 29 in the base plate 10, the slot 29 being positioned to one side of the vertical center line (Fig. 1) of the base plate 10 and being of a width to substantially snugly receive the rod 27 (see Fig. 3) so that the remaining portion of the rod 27 projects into the interior of the enclosure formed by the base plate 10 and the cover 30 (see Fig. 2); the slot 29, furthermore, forms a guide for guiding the rod 27 in its movement in a vertical plane and steadies the rod, in coaction with the mounting of the rod 27 to the external mounting structure, against lateral or side strains, as viewed in Figs. 1 and 3. The rod 27 may be of round cross-section and tightly secured or fitted into a drilled hole 20^a (Fig. 2) in the heavy shank of the actuator lever 20.

Next I provide a lever structure 31 and a striker lever or link 32, and arrange them to be coaxially pivoted with the lever structure 31 coacting with a portion of the rod 27 that projects through the slot 29. The lever structure is preferably in the form of a sheet-metal stamping, conformed to U-shape, having an inner plate 33 (Figs. 3 and 1) shaped as is better shown in Fig. 3, and an outer and peripheral plate 34 shaped as is better shown in Fig. 1, the two being integrally joined by a cross-plate 35. Inner plate 33 is provided with a hole 36 (Fig. 3) and outer plate 34 is provided with an open-ended slot 37, the inner end of which is rounded or curved and is coaxial with the hole 36 in the opposite plate so that the two may form a pair of spaced bearings.

The striker link or arm 32 (see Fig. 2) may also be in the form of a sheet-metal stamping, being given the shape of an inverted U and hence having two depending spaced arms 38 and 39 provided with ears 40 and 41, respectively, to form in effect trunnions; the striker lever 32 has an upward extension 42 to which the striker head 18 is secured in any suitable way.

To the left of the lower end of the slot 29 (Fig. 3) the base plate 10 is provided with a hole 43 (Fig. 2) with which the hole 36 in the back plate 33 (Fig. 3) is aligned by positioning the U-shaped lever structure 31 with the plate 33 resting flatwise against the base plate 10, and with the holes 36 and 43 thus in register, the trunnion 40 of the striker arm 32 is passed into both holes (see Fig. 2), thus providing a pivotal support from the base plate 10 of both the arm 38 of the striker lever 32 and the back plate 33 of the lever structure 31. As this assemblage is carried on, the opposite trunnion 41 (Figs. 2 and 1) is passed into the slot 37 of the front plate 34 (Fig. 1) and bottomed in the slot, leaving a substantial portion of the trunnion 41 projecting forwardly (to the left in Fig. 2) of the front plate 34.

Thereupon a U-shaped bearing bracket 45, also conveniently in the form of a sheet-metal stamping, is positioned and secured in place to provide a bearing for the still projecting portion of the trunnion 41. The bracket 45 has a front portion 45^a provided with a hole 45^a (Figs. 1 and 2) into which the trunnion 41 is received and two par-

allel side arm portions 45^c and 45^d (Figs. 1 and 3) which extend rearwardly to the base plate 10 by which they may be secured to the base plate 10 by screws or bolts 46 (Fig. 1).

5 A tensioned coiled spring 48 (Figs. 1 and 2) is connected between the cross-plate 35 of the lever structure 31 and the cross-portion of the forked or U-shaped striker lever 32, and by its component of upward pull on the lever frame 31, as viewed in Fig. 1, prevents sliding disengagement 10 between the trunnion 41 and the slotted front plate 34, insuring that the former always bottoms in the slot.

The side arms 45^c and 45^d (Fig. 3) of the bearing bracket 45 also coact to limit pivoting movement of the lever frame 31, the rear plate 33 and front plate 34 of which have extensions 33^a and 34^a, respectively, that present parallel edges for engaging simultaneously with the horizontal side arm 45^c and thus limit the counter-clockwise rotary movement of the lever structure 31. The back plate 33 (Fig. 3) has a lever-like extension 33^b that presents an edge 33^c to engage the other horizontal side arm 45^d and thus limit rotary movement in clockwise direction, and it also presents a cam-like edge 33^f for coaction with the rod 27 that projects through the slot 29 which the lever-like extension 33^b overlies, as is better shown in Figs. 3 and 2.

30 The spring 48 is so proportioned and tensioned as to tend to swing the lever structure 31 and the striker lever 32 in directions toward each other, whether the line of pull of the spring 48 is to the right of the common axis of these parts, as shown

35 in Fig. 1, or is to the left thereof, the line of pull of the spring passing through the "dead center" or this common axis upon transition from one position to the other and the spring 48 bodily partaking of shift in its position by way of the free

40 space provided between the arms 38—39 of structure 32 (Fig. 4), it being noted that, even though the free end portion of the rod 27 projects leftwardly (in Fig. 2) beyond the spring 48, the rod 27 is out of the path of movement of the spring

45 48 and also of the swinging lever 32 because of its substantial lateral displacement (Figs. 1 and 3) from the center line of the base plate 10. Hence, in installation, varying extents of inward projection of the rod 27 through the base plate

50 10, varying with the thickness of the door panel, need not give any concern for it is impossible to interfere with the movement of the moving parts.

A coiled spring 50 (Figs. 3 and 1) connects the cross-plate 35 and the side arm 45^d of the bearing bracket 45 and biases the lever structure 31 always to the position shown in Fig. 3.

The driving connection between the lever structure 31 and the striker arm 32 being solely by way of the spring 48, suitable means are provided to control the range of swing of the striker head 18 so that it does not damp the vibrating sounding element after striking it, and a convenient means for this purpose comprises a U-shaped sheet-metal frame 51 (Figs. 1 and 2) secured to the base plate 10 and having projecting forwardly therefrom arms 51^a and 51^b that terminate in the paths of movement, respectively to the left and right, of the tensioned spring 48 (Fig. 1), and, if desired, the arms 51^a and 51^b may be provided with elements 51^c and 51^d made of any suitable non-metallic material so that the impact of the spring thereagainst does not set up any disturbing sound. The elements 51^c and 51^d need not be resilient, though they can be made of rubber, resilient or not, as may be desired. The arms 51^a and 51^b,

after completion of assembly of the frame 51 to the base plate 10, as by spot welding or screws or the like, may be bent into respective positions such that, when engaged by the spring 48 in either of the clockwise or counter-clockwise positions of the arm 32, the striker head 18 is held by an appropriate distance out of contact with the adjacent sounding element.

When the external actuator 19 is given a small counter-clockwise angular movement (Fig. 2), the downward sweeping movement of the rod 21 causes a clockwise rotary movement of the lever structure 31 by its camming action along the cam edge 33^c of the lever extension 33^b (Fig. 3). At the start of the clockwise swing of the frame 31 (Fig. 3), resistance to turning movement might be considerable, but that is overcome by the unique camming action of the rod 27 along the cam edge 33^c which is upwardly inclined at a considerable angle (see Fig. 3) during the first portion of the moving stroke, the cam edge during this portion making an acute angle with the left-hand wall of the slot 29, the downward movement of rod 27 acting in effect by a force-multiplying wedging action, thus dependably starting the swinging of the lever structure 31 against the tension of springs 50 and 48. The swinging motion is continued thereafter principally by the accompanying lever action of the rod 27 on the lever arm 33^b, and, since the lower end of spring 48 has passed "dead center," that being the line extended downwardly along the striker arm 32 as seen in Fig. 1, the energy stored in the spring 48 is expended to quickly swing the arm 32 in counter-clockwise direction and impact it against the sounding element 14; the spring 48, however, first striking the element 51^e on the arm 51^a, but, because of the resiliency of the spring 48 and the momentum of the weighted striker head 18, the latter biases what would otherwise be an "at rest" position to strike the sounding element 14, from which it rebounds, aided by the coaction of the spring 48 with the element 51^e, so as not to damp the vibrating element 14.

In this relationship of the parts, the extent of rotary movement of the lever structure 31 in clockwise direction is limited by the engagement of the lower edges of the plate parts 33 and 34 against the under edge of the side arm 45^c, these parts thereby also limiting the extent of downward swing of the operating rod 27.

If the actuating member 19 (Figs. 4 and 2) is then released, the energy stored in spring 50 (Fig. 3) commences the counter-clockwise rotary movement of the lever frame 31, thus again tensioning the spring 48 and storing energy in it, until the lower end of spring 48 biases the "dead center" position, whence its energy is expended to swing the striker structure in clockwise direction toward the other sounding element 15 which it strikes by biasing the limit of its movement as determined by the spring 48 and the element 51^f, the spring 48 yielding under the energy of motion of the striker head, but, aided by some rebound of the striker head from the sounding element 15, restoring the striker head to its "at rest" position (as shown in Fig. 1) out of contact with the sounding element 15, and thus again not permitting damping of the vibrations thereof. The action takes place quickly, the counter-clockwise movement of the lever frame 31 being limited by the engagement of the front and back plates 33 and 34 with the upper edge of the side arm 45^c, as shown in Figs.

1 and 3, and being accompanied by the camming upwardly along the slot 29 of the operating bar 27 and thereby restoring the external actuator 19 to its normal "at rest" position, from which it is to be moved upon a subsequent actuation.

5 In the normal or "at rest" position of the parts, as shown in Figs. 1 and 3, the lever extension 33^b of the back plate 33 covers over a substantial portion of the slot 29, and the cam edge 33^c forms in effect a bottom edge for so much of the slot 29 that is left free to receive the rod 27 when installing the two external and internal portions of the mechanism, and, in so doing, the lever portion 33^b fixes the height at which the base plate 10 is to be secured to the panel 12 after the external actuator mechanism has been secured to the external face of the panel 12 and the actuator arm 20 thereof given a somewhat inwardly-swung position, as indicated in Fig. 2. Installation is thus simplified, even though any angularity of the operating rod 27 relative to the horizontal causes different vertical displacements of the base plate 10 relative to the external actuator mechanism for different thicknesses of panel 12.

10 25 The cover or closure 30, which may be a sheet-metal drawing, closes over the entire mechanism, having side walls 30^a which telescopically interfit with the flange 11 of the base plate 10 to which it may be secured in any suitable manner, preferably detachably. In the side walls adjacent the sounding elements 14 and 15, suitable apertures 30^b may be provided for sound transmission, the entire enclosure functioning preferably as a resonator.

15 30 35 It will thus be seen that there has been provided in this invention a musical chime signalling construction in which the various objects hereinbefore noted, together with many thoroughly practical advantages, are successfully achieved.

20 40 45 As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

I claim:

25 50 55 60 65 1. In a signalling device comprising a frame having two sounding elements mounted thereon in spaced relation, a striker having means movably supporting it for movement into successive impact with said sounding elements, actuating means comprising a rock lever structure pivotally supported by said frame and having mechanical connection with said striker to actuate the latter in response to rocking movement of the rock lever structure, said frame having a slot therein for the projection thereinto of an external actuator, and an actuator projecting through said slot and having means mounting it for movement lengthwise of said slot, said rock lever structure having a lever-like arm substantially overlying said slot and having a cam surface engaged by said actuator to rock said rock lever structure in response to actuation of said actuator.

70 75 2. In a signalling device for mounting on a panel wall or the like and comprising a sounding element, a lever having a striker head, and means or pivotally mounting said lever, means for actuating said lever comprising, a member having a plurality of arms, and pivotal mounting means for said member, actuator means adapted to ride on one of the said arms of said member as a cam.

surface to translate rectilinear action into rotative action thereby to rotate said member, stop means in the rotative path of said member and adapted by contact against the respective arms of said member to limit the rotative movement of said member, spring means interconnecting said member and said striker lever intermediate its ends, and other spring means biasing said member so that its said spring means when at rest is angularly related to said striker lever and in action is moved alternately from one side to the other side of the said pivot of the striker lever as said member is rocked back and forth on its pivotal mounting within the limits permitted by its said stop means.

3. In a signalling device comprising a frame, two sounding elements mounted thereon in spaced relation, a lever carrying a striker for alternate impacting against said sounding elements, a rock lever structure, and means coaxially pivoting said rock lever structure and said lever on said frame, and spring means interconnected between said striker lever intermediate its ends and said rock shaft structure whereby said striker lever is actuated with a snap action in response to rocking of said lever

structure in either direction, and means for actuating said lever structure to rock it.

4. A signalling device as claimed in claim 3 in which the means for rocking said rock lever structure comprises an actuator, and means for mounting said actuator for rectilinear movement in frictional engagement with said rock lever structure.

5. A signalling device as claimed in claim 3 in which said spring means is angularly disposed with respect to said striker lever at all times except momentarily when passing from one side to the other side of the pivot of said striker lever during each swing of said lever structure and striker lever.
